UNITED STATES PATENT OFFICE

CHARLES R. HULTGREN, OF CHICAGO, ILLINOIS, ASSIGNOR TO S. KARPEN & BROS., OF CHICAGO, ILLINOIS, A CORPORATION OF WEST VIRGINIA

SOFA BED

Application filed February 3, 1927. Serial No. 165,557.

This invention relates particularly to sofa-beds of the type in which the front bed-section has a bodily movement, in converting from bed-form to sofa-form to a position above the rear bed-section, which is lowered during the closing action.

The primary object is to provide an improved device of simple and staunch construction, which can be manufactured at moderate cost, which can be readily assembled, and which can be converted from bed-form to sofa-form and vice versa, with ease.

The invention is illustrated in its preferred embodiment in the accompanying drawings, in which—

Fig. 1 is a broken vertical sectional view of a sofa-bed embodying the invention, in extended condition; Fig. 2, a broken vertical sectional view showing the structure in folded condition, the cushions and bed-sections being shown in end elevation; Fig. 3, a view similar to Fig. 1, but with the springs and cushions removed; Fig. 4, a view similar to Fig. 3, but showing the structure in the process of folding; Fig. 5, a broken horizontal sectional view taken as indicated at line 5—5 of Fig. 3; Fig. 6, a broken vertical sectional view with the upholstery springs and cushions, or mattress-sections, removed; Fig. 7, an enlarged broken vertical sectional view taken as indicated at line 7 of Fig. 3; Fig. 8, a plan view of a detachable mounting-bar employed; Fig. 9, a plan view of a plate adapted to be secured to the inner side of the end-standard of the main frame; and Fig. 10, an elevational view of the member shown in Fig. 9.

In the construction illustrated, A designates a main frame provided with end-standards A', a back A², rear longitudinal connecting members A³, and a front longitudinal connecting member A⁴; B, B', a pair of mounting-bars, one at each end of the main frame, detachably mounted on bracket-plates B² with which the end-standards are equipped at the inner sides of their lower front portions; C, C', a front pair of elbow-levers which have their short arms connected by pivots 1 to the front portions of the mounting-bars and which have their long

arms pivotally connected at points 2 with the front bed-section; D, D', a rear pair of elbow levers having their short arms connected by pivots 3 with the mounting-bars B, B' and which have their long arms connected, by pivots 4, to the rear portion of the front bed-section; E, a front bed-section carried by the long arms of the bell-crank levers and provided with a mattress-section, or cushion, E'; F, a rear bed-section slidably mounted on guides, or clips, 5 and 6, which are connected, respectively, with the elbow-portions of the front elbow levers and the rear bell-crank levers by pivots 5^a and 6^a, the rear bed-section being equipped with upholstery springs F' and a surmounting loose cushion F² which is adapted to serve as a seat-cushion when the structure is in folded condition; G, G', a pair of control links connected with the rear bed-section by pivots 7, the rear ends of these links, in the illustration given, being connected by means of pivots 8 with lugs 9 carried by the rear ends of the mounting-bars B and B'; H, H', counterbalance springs connected at their rear ends with studs 10 with which the rear portions of the mounting-bars are equipped, and connected at their front ends by studs 11 with lugs 12 with which the elbow-portions of the rear elbow levers are equipped; I, I', legs connected by pivots 13 with the front portion of the front bed-section; and J, J', a pair of links controlling the movements of the legs, said links being connected at their rear ends, by pivots 14, with the long arms of the front elbow levers and being connected at their front ends, by pivots 15, with short extensions with which the legs are equipped at their upper ends.

The main frame of the sofa-bed may be of any desired construction. In the illustration given, the end-standards A' are rigidly connected together by the rear connecting members A³ and the front connecting member A⁴.

The bracket-plates B² are rigidly attached to the lower front portions of the end-standards, as by means of screws 16, and are provided at their upper edges with inclined slots 17 which receive studs 18 with which

the mounting-bars B and B' are equipped. The mounting-bars preferably are provided at their front ends with lateral extensions 19 which are secured to the front connecting member A⁴, as by means of screws 19^a.

5 The front and rear pairs of elbow levers are, in the illustration given, of the same size and shape, and are adapted to carry the front and rear bed-sections by parallel movements. It is not essential that the front elbow levers be of the same shape, as the rear elbow levers, however. In the illustration given, the elbow levers and bed-sections are so connected and mounted that 10 when the structure is in open condition, the frame of the front bed-section is elevated some distance above the frame of the rear bed-section. This will be noted particularly in Fig. 1; and it will be noted there that the upholstery springs F' serve to support the 15 upholstery springs F' serve to support the cushion F² flush with the cushion on the mattress-section E'. When the structure is to be folded, the cushion F² is first thrown upon the mattress-section E', and the folding 20 action is then permissible.

The frame of the front bed-section is shown provided with end-members 20 with which the long arms of the front and rear elbow levers are pivotally connected. It is 25 desirable to connect one pair of levers rigidly together, so that all of the levers will turn properly together and racking of the structure will be avoided. In the illustration given, this is accomplished by connecting 30 the extremities of the long ends of the arms of the front elbow levers by a bar 21 whose ends are rigidly secured to the extremities of said arms. The bar extends through the pivots 2, and thus the bed-section is pivotally 35 connected with the front elbow levers at these points.

The clips 5 and 6, which may be termed 40 slides, are joined pivotally to the elbow-portions of the bell-crank levers, as has been stated; and these clips are of a form to permit them to slide with relation to the end-members 22 of the frame of the rear bed-section. Thus, the rear bed-section is 45 shiftably mounted on the elbow-portions of the elbow levers. The control links G and G' which are connected with the end-members 22 permit only a limited forward and rearward movement of the rear bed-section during the raising and lowering movements 50 thereof. In the position shown in Fig. 1, the control links are substantially horizontal. During the folding operation, they swing 55 downwardly to the position shown in Fig. 2, which results in the rear bed-section being shifted rearwardly a short distance.

The upholstery springs F' are shown as 60 mounted on slats 23 with which the frame of the rear bed-section is provided; and the upholstered springs are shown as contained 65 in an envelope, or covering, 24, which, how-

ever, is so applied as not to interfere with the movement of the slides 5 and 6 connected with the end-members 22.

The counterbalance springs H and H' are under tension when the structure is in bed-form and also when the structure is in sofa-form. To convert the structure from sofa-form to bed-form, a moderate lifting and pulling action is exerted on the front bed-section. The springs H aid in elevating the front bed-section; and, in the unfolding operation, the elbow levers carry the front bed-section to the extended position. The cushion F² is then placed upon the springs F' of the rear bed-section, and bedding may then be applied.

In converting from bed-form to sofa-form, the cushion F² is first placed upon the mattress-section E' of the front bed-section, and the folding operation is performed by lifting the front bed-section and shoving it rearwardly until it assumes a position above the rear bed-section. In the extended form of the structure, the long arms of the rear elbow levers may rest upon the long arms 90 of the front elbow levers.

The construction is strong and durable, may be operated with ease, and may be manufactured at moderate cost.

The foregoing detailed description has 95 been given for clearness of understanding only, and no unnecessary limitations should be understood therefrom, but the appended claims should be construed as broadly as 100 permissible, in view of the prior art.

What I regard as new, and desire to secure by Letters Patent, is:

1. In a sofa-bed; a main frame; a pair 105 of elbow levers having their short arms pivotally mounted on each end of said frame; a rear bed-section, means by which the rear section is slidably mounted on the elbow-portions of said levers; and a front bed-section pivotally mounted on the extremities of the long arms of said levers.

2. In a sofa-bed; a main frame; a front 110 pair of elbow levers and a rear pair of elbow levers adjacent the ends of said frame and having their short arms pivotally connected therewith; slides pivotally mounted on the elbow-portions of said levers; a rear bed-section shiftably mounted on said slides; and a front bed-section pivotally mounted on the long arms of said 115 levers.

3. In a sofa-bed; a main frame; a pair 120 of elbow levers having their short arms pivotally mounted on each end of said frame; a rear bed-section, means by which the rear section is slidably mounted on the elbow-portions of said levers; a front bed-section pivotally mounted on the extremities of the long arms of said levers; and means for controlling the position of the 125 130

rear bed-section during the raising and lowering thereof.

4. In a sofa-bed; a main frame; a front pair of elbow levers and a rear pair of elbow levers adjacent the ends of said frame and having their short arms pivotally connected therewith; slides pivotally mounted on the elbow-portions of said levers; a rear bed-section shiftably mounted on said slides; a front bed-section pivotally mounted on the long arms of said levers; and means for controlling the position of the rear bed-section during the raising and lowering thereof.
5. In a sofa-bed; a main frame; a front pair of elbow levers and a rear pair of elbow levers adjacent the ends of said frame and having their short arms pivotally connected therewith; slides pivotally mounted on the elbow-portions of said levers; a rear bed-section shiftably mounted on said slides; a front bed-section pivotally mounted on the long arms of said levers; and means for controlling the position of the rear bed-section during the raising and lowering thereof.
15. In a sofa-bed; a main frame; a front pair of elbow levers and a rear pair of elbow levers adjacent the ends of said frame and having their short arms pivotally connected therewith; slides pivotally mounted on the elbow-portions of said levers; a rear bed-section shiftably mounted on said slides; a front bed-section pivotally mounted on the long arms of said levers; and control links connected at the rear with said frame and at the front with said rear bed-section and permitting limited shifting movement of said rear bed-section.
6. In a sofa-bed; a main frame; a pair of front elbow levers having their short arms pivotally connected with end-portions of the main frame; a pair of rear elbow levers having their short arms pivotally connected with the end-portions of said main frame, said front and rear levers being approximately the same size and shape; a front bed-section pivotally connected with the long arms of said levers; a pair of slides pivotally connected with the elbow-portions of said levers; a rear bed-section slidably connected with said slides; and means for preventing undue forward and rearward movements of the rear bed-section while it is being elevated or lowered through the medium of said elbow levers.
45. In a sofa-bed; a main frame; front and rear pairs of elbow levers having their short arms pivotally connected with said frame; slides pivotally connected with the elbow-portions of said levers; a rear bed-section shiftably mounted on said slides; control links governing the position of said rear bed-section during the raising and lowering thereof; counterbalance springs connected with the main frame and with the rear pair of levers; and a front bed-section pivotally connected with the long arms of said levers.

CHARLES R. HULTGREN.
